Edna H. Strachan, Ann Arbor, Mich.

Application July 19, 1948, Serial No. 147,670

Term of patent 3½ years

(Cl. D17—3)

To all whom it may concern:

Be it known that I, Edna H. Strachan, a citizen of the United States of America, residing at Ann Arbor, in the county of Washtenaw and State of Michigan, have invented a new, original, and ornamental Design for a Clip, of which the following is a specification, reference being had to the accompanying drawing, forming a part thereof, wherein:

Fig. 1 is a top plan view of a clip, showing my new design;

Fig. 2 is a side elevational view;

Fig. 3 is an end view; and

Fig. 4 is a longitudinal, vertical sectional view taken on the line 4—4 of Fig. 1.

I claim:

The ornamental design for a clip, substantially as shown.

EDNA H. STRACHAN.
